United States Patent Office

Des. 233,906
Patented Dec. 10, 1974

233,906

BEAD

Harold Roger, 370 1st Ave.,
New York, N.Y. 10010

Filed Sept. 10, 1973, Ser. No. 395,825

Term of patent 14 years

Int. Cl. D11—01

U.S. Cl. D45—16 R

FIG. 1

FIG. 3

FIG. 2

FIG. 1 is a side elevational view of a bead showing my new design;

FIG. 2 is a plan view; and

FIG. 3 is a sectional view taken on line 3—3 of FIG. 2.

I claim:

The ornamental design for a bead, as shown and described.
